UNITED STATES PATENT OFFICE.

JAMES L. JUDGE, OF MINNEAPOLIS, MINNESOTA.

SEAL FOR STEAM-RADIATORS.

1,134,135.

Specification of Letters Patent. Patented Apr. 6, 1915.

Application filed September 2, 1913. Serial No. 787,628.

To all whom it may concern:

Be it known that I, JAMES L. JUDGE, citizen of the United States, and a resident of Minneapolis, Hennepin county, Minnesota, 5 have invented certain new and useful Improvements in Seals for Steam-Radiators, of which the following is a specification.

My invention relates to steam radiators having supply and return pipes. 10 The object of the invention is to provide a seal in the return pipe which will allow the water of condensation to be drawn out of the radiator without the use of the ordinary air valve generally employed in steam 15 radiators.

A further object is to provide a seal which will allow the radiator to discharge the water of condensation and accumulation of air without the "pounding" frequently incident 20 to the discharge of the water from a radiator.

Other objects of the invention will appear from the following detailed description.

My invention consists generally in various 25 constructions and combinations, all as hereinafter described and particularly pointed out in the claims.

In the accompanying drawings forming part of this specification, Figure 1 is a side 30 elevation of a steam radiator embodying my invention, Fig. 2 is a detail sectional view of the seal or trap, Fig. 3 is a sectional view on the line x—x of Fig. 2.

In the drawing, 2 represents a radiator of 35 any ordinary or preferred type, having a steam supply pipe 3, and 4 is a casing having a vertical socket 5 for a nipple 6 which communicates with the last section of the radiator, and a similar horizontal socket 7 for 40 the return pipe 8 which preferably extends under the radiator, as usual in fittings of this kind. A plug 9 is tapped into the lower end of the casing 4 concentric with the nipple 6 and having an outer surface adapted 45 to receive a wrench, and provided with a tube 10 preferably formed integrally with the plug and having a tapered upper end 11 to fit a seat 12 formed on the interior of the casing. This tube extends downwardly in 50 the casing, preferably to a point below the level of the pipe 8, and it is provided with a series of ports 13 which form communicating passages leading from the radiator and the interior of the tube into a space between 55 said tube and the wall of the casing 4 which communicates with the return pipe 8,

so that the water of condensation collecting in the radiator and flowing out through the nipple 6 is compelled to pass down through the tube 10 and out through the ports 13 before reaching the return pipe 8. The ports 13 being below the level of the return pipe, the water of condensation collecting within the casing and the tube submerges these ports and forms a seal, thereby preventing 60 the steam from flowing from the radiator into the return pipe.

A baffle 14 is provided within the casing, extending upwardly and partially across the opening to the pipe 8, thereby compelling 70 the water to rise within the casing above the ports 13 and flow over the baffle 14 before entering the return pipe. This baffle is also preferably provided with a small port 15 through which any water of condensation 75 which may accumulate in the casing may escape slowly from said casing and flow into the return pipe. There will always be slow escape of water from the casing through the port 15 into the return pipe 8. This will be 80 so slow that ordinarily the water of condensation will accumulate in the casing to such an extent as to flow over the top of the baffle 14, thereby forming a seal in the casing, but when the water of condensation 85 ceases to accumulate, or accumulates very slowly, the escape through the port 15 will be sufficient to lower the water in the casing to the upper edges of the ports 13, which are substantially on a level with the small port 90 15. The small amount of water that will remain in the casing cannot do any harm, even if it is frozen in said casing, whereas, if the water were permitted to remain in the casing to the height of the top of the baffle 14, 95 and this larger amount of water became frozen, it might injure the casing. The removal of the plug 9 allows access to the port 15 in the casing, should it become clogged. The upper end of the tube 10 forms a close 100 joint with the seat 11, and near this seat I prefer to provide a comparatively small port 16, which will allow the air accumulated in the radiator to pass down through the return pipe above the water of condensation 105 therein. This port will also allow the passage of a very small volume of steam, sufficient only to insure the desired circulation of steam in the radiator.

In the operation of the radiator, the water 110 of condensation will flow into the casing 4 and pass out through the ports 13 and rising

above the baffle 14 will pass off through the return pipe. A sufficient amount of water will remain in the bottom of the casing to form a seal at that point and prevent the discharge of steam through the return pipe, while as fast as the water accumulates in the radiator, it will be trapped out and carried off through the return pipe. As hereinbefore explained, there will always 10 be a small flow of water through the port 15, and when the water is not accumulating in the casing, or is accumulating very slowly, the escape through the port 15 will be sufficient to lower the water in the casing 15 to the level of the port 15, thereby leaving only a small amount of water in the bottom of the casing, which will not harm the casing in case it becomes frozen therein. Any air that may accumulate in the radiator 20 will pass down into the tube 10 and through the port 16 and along the upper portion of the return pipe.

This device possesses a decided advantage 25 over other seals of this type in that the parts are all readily accessible upon the removal of the plug 9, without the necessity of disturbing the return pipe connections.

I claim as my invention:

1. The combination, with a radiator and 30 a return pipe therefor, of a casing having an open upper end connected with the radiator and an opening in its side wall connected with said return pipe, means in the lower portion of said casing for trapping the water of condensation from said radiator, said means having a port located near the upper portion of said casing for the passage of air from said radiator into 35 said return pipe.

40 2. The combination, with a radiator and a return pipe therefor, of a casing having an open upper end connected with the radiator and a side opening connected with said return pipe, a tube arranged in said casing 45 having a comparatively large opening in its lower portion for the passage of water of condensation from said tube to said return pipe, and a comparatively small opening in its upper portion for the passage of air; said casing having a trap for collecting the water of condensation and sealing said large opening against the passage of steam.

50 3. The combination, with a radiator and

a return pipe therefor, of a casing having its upper end connected with said radiator and a side wall connection with said return pipe, a tube arranged in said casing and having an open upper end communicating with said radiator and forming a close joint with said casing above said return pipe, 55 said tube having ports in its lower walls leading from said radiator to said return pipe, said ports being below the level of said return pipe, whereby the water of condensation accumulates around said tube and 60 seals said ports against the passage of steam from said radiator; the upper portion of said tube having a comparatively small port for the passage of air from said radiator into the upper portion of said return pipe. 70

4. The combination, with a radiator and a return pipe therefor, of a casing interposed in said return pipe, a plug removably fitting within said casing, a tube mounted on said plug and seated at one end in said 75 casing and communicating with said radiator, the lower portion of said tube having ports therein leading from said radiator to said return pipe and below the level of said return pipe; the water of condensation accumulating around said ports and sealing them against the passage of steam from said radiator; the upper portion of said tube having a comparatively small port therein for the passage of air from said radiator 80 to said return pipe.

5. The combination, with a radiator and a return pipe therefor, of a casing interposed in said return pipe, a plug tapped into said casing, a tube mounted on said 90 plug and communicating at one end with said radiator and having ports in its lower walls leading from said radiator to said return pipe, said ports being below the level of said return pipe, and a baffle extending partially across said return pipe between it and said tube and having a port therein, substantially level with the ports in said tube.

In witness whereof, I have hereunto set 100 my hand this 25th day of August, 1913.

JAMES L. JUDGE.
